COLLAPSIBLE CARTON

Harold E. Rounds, Great Neck, N. Y.

Application June 11, 1934, Serial No. 730,101

1 Claim. (Cl. 206—44)

My invention relates to improvements in cartons or containers, and more particularly has reference to and is illustrated in the accompanying drawings in its application to a stiff paper carton of collapsible form adapted for carrying or merchandising small articles such as the candle-holders for birthday cakes. Naturally, an article of this type must be cheap, simple and serviceable, and in the preferred design of my carton, the same may be made of a single integral piece of card or other material which may be carried flat in stock, and which may be folded quickly and easily to assemble a complete carton, one form thereof including a separate ring or framelike member which may be inserted into the top with a piece of transparent material such as Cellophane, for providing a window through which the article may be inspected.

Referring to the accompanying drawings, Fig. 1 illustrates in perspective, in partly formed position, a suitable form of carton embodying an application of my invention. Fig. 2 is a perspective view of the same in completely folded or formed position, parts being broken away. Fig. 3 is a cross-sectional view, on the line 3—3 of Fig. 4, showing the position of a forming block which may be used in assembling the carton and for inserting the holders, a suitable window and frame being introduced at the top. Fig. 4 is a longitudinal sectional view of the completely formed container with the window and the candle-holder inserted, and with the assembling block in position. Fig. 5 is a perspective view of a suitable form of assembling block. Fig. 6 indicates in perspective, a suitable form of top insert frame for applying a sheet of transparent material, such as shown in perspective in Fig. 7. Fig. 8 illustrates in perspective, in partly formed position, a preferred form of carton embodying an application of my invention. Fig. 9 shows the same in perspective in more completely formed position, parts being broken away. Fig. 10 shows the same in side elevation, completely formed. Fig. 11 is a cross-sectional view on the line 11—11 of Fig. 10. Fig. 12 is a plan view looking down upon Fig. 10. Fig. 13 is a perspective view of a piece of transparent material such as Cellophane which may be folded into the top of the carton as formed to provide a window, and Fig. 14 is a similar view to Fig. 11, showing modifications.

The complete carton consists of a single sheet of paper or card, having a central portion 8, which is bent rectangularly, the free ends being suitably secured in overlapped position as indicated in 9, thus forming a rectangular tubelike

body portion from which extends upwardly a flap comprising three sections 10, 11 and 12, the section 12 being bent down at right angles as shown to advantage in Fig. 3, then transversely as shown in said figure at 11, and then upwardly as shown therein at 10. The lower flap comprises sections 13, 14 and 15, the latter of which is bent upwardly as indicated to advantage in Fig. 3 at 13, then transversely as shown therein at 14, and then upwardly at the opposite side as shown at 15, thus providing a rectangular tube structure with two transverse pieces bent therefrom by the aid of the score lines 16, the lower piece 14 being preferably provided with spaced holes such as 17, and the upper piece 11 with cross-cuts such as 18. The candle-holders 19 which are shown in the form of flowers usually made of clay composition and provided with pins 20, may now be inserted, first through the cross-cuts 18 and then through the holes 17, the frictional engagement of the cross-cuts holding the same securely in position, so that the charged cartons thus formed may be readily packed in boxes for shipment, and of course it will be understood that slits or other forms of penetratable portions may be provided in lieu of the cross-cuts 18 or holes 17, if desired.

When the carton has been formed or loaded as aforesaid, I may apply a rectangular frame 21 of card, such as shown in Fig. 6, the same having exterior dimensions about equal to the interior dimensions of the carton except as to the height, and by now first placing a small piece of cellulose 22, shown in Fig. 7, over the top of the carton, and by pressing down upon the frame 21, the cellulose or Cellophane as the case may be is forced down tautly into the body of the carton as shown, the margin thereof being squeezed and frictionally retained between the turned in flaps 10, 12, of the carton, thus providing a neat uniform window-like finish over the top of the carton.

Also for assembling the carton and for charging the same, a suitable jig or block, such as shown in Fig. 5, may be employed. This consists of a base 23 and support 24 thereon or formed therewith, from which extend upwardly, thin tubes 25 of an outer diameter sufficient to permit the same being pushed through the holes 17 in the section 14 of the lower flap, reaching upwardly to a point immediately beneath the upper transverse wall or partition 11, which may thereafter be folded in as before described, and the pins 20 of the holders being now pushed through the upper partition 11 at points indicated, traveling down through the tubes 25 through the lower portion 14, when the assembling and loading is thereby complete, un-

less it is desired to apply the top insert frame over the transparent sheet to form the window as above described. These operations can be manipulated very rapidly and insure a neat strong casing or 5 packaging of the holders which are visible for inspection at all times.

In the modification shown in Figs. 8 to 13 inclusive, the body portion 26 is formed by folding the blank laterally as before described, overlapping 10 and securing the free ends as indicated at 27. A flap having sections 28, 29 and 30, separated by score lines 31, projects upwardly from the back of the body portion, and a flap having sections 32, 33 and 34, separated by score 15 lines 35, projects downwardly from the back of the body portion, as shown to advantage in Fig. 8, end flaps 36 and 37 being also provided, and likewise a cut-out top 38 having side frame members 39, 40 hinged to the top of the front 26 as 20 shown. The intermediate sections 29, 33 of the top and bottom flaps are also preferably perforated at points 41, 42, which come into vertical alignment when the carton is formed or folded. In forming the carton, section 32 of the bottom 25 flap is folded inwardly parallel with the front as shown to advantage in Fig. 11, then at right angles across the interior of the carton, and downwardly at the back. Section 30 of the top flap is folded inwardly parallel with the front 30 of the carton, then at right angles across the interior thereof, and then downwardly parallel with the back of the carton as shown. This brings the holes in the sections 29, 33 into alignment and the pins of the candle-holders are readily inserted as shown.

The end flaps 36, 37 are turned in and the small sheet of transparent material is laid across them as indicated at 43, the rear margin being first extended into the top of the carton as shown at 35

43', if desired. The front margin of the transparent sheet may now be tucked in with the end flap 38 of the top frame hinged to the side members 39, 40 by score lines 44, 45 and to the top front edge of the body of the carton by score lines 46, 47 serving as hinges, thus providing a neat, easily assembled and economically produced display carton of attractive appearance.

In the modification shown in cross-section in Fig. 14, the top and bottom flaps are preferably 10 at the front and back of the carton respectively, the top front flap having three sections bent Z-shape, first parallel with the front as at 38', then across the carton as at 29', and then down parallel with the opposite side of the carton as at 28'. The bottom inverted U-shaped flap extends down from the back of the carton and is bent upwardly therein parallel with the back of the carton as shown at 32', then across as at 33', and then down parallel with the front of the carton as at 34'.

Of course it will be understood that various modifications may be made in the construction and arrangement of parts, without departing from the spirit of the invention as claimed.

I claim:

A package of the character described having a substantially rectangular tube-like portion, foldable perforated flaps above and below the same adapted to be folded therein to provide 30 partitions within said tube, end flaps at the top of said tube, a piece of transparent material thereon, and a flap hinged to the top of said tube opposite said first mentioned flaps and over said transparency having a cut away portion 35 through which the contents of said package can be seen through said transparent material.

HAROLD E. ROUNDS.
